RULING DEVICE

Steven A. Zgraniik, Berwyn, Ill., assignor to
Douglas Aircraft Company, Inc., Santa Monica,
Calif.

Application November 22, 1946, Serial No. 711,646

5 Claims. (Cl. 101—93)

1

This invention relates to a ruling device which may be adapted to existing writing machines or become a fixed part of machines to be manufactured.

For a long time a satisfactory device has been sought for ruling vertical columns on paper simultaneously with the printing accomplished by certain writing machines, and especially a device capable of making carbon copies. The most useful instance for such a device would be for tabulating machines. At the present time it is necessary to use ruled paper and because of the variety of information recorded, a large variety of ruled paper must be kept on hand. Often styles and procedures of accounting change, thereby rendering obsolescent most or all stock on hand. A satisfactory ruling device will obviate the present difficulties and save the increased cost of the ruled paper.

A number of devices have heretofore been proposed for ruling paper on typewriters, accounting machines and time recording machines. Among such devices were: a combination which comprised an ink pad over which disks were rolled prior to contacting the paper on the machines; an ink well together with pen or stylus which pressed upon the paper; or simply a device possessing no automatic features but requiring a separate and distinct operation to be performed.

These devices have not been entirely successful for a number of reasons. The pads must be inked and the wells filled frequently and adjustments are necessary to obtain a line of proper density. Further, the device must be disengaged so that no ruling will appear before figures are to be printed and finally only one original copy may be made.

The device of the present invention not only overcomes such objections and deficiencies but possesses other advantages. With the device of the present invention, as many rulings as desired may be made to separate the columns of figures. Thus, the use of the present device also obviates the necessity of large inventories of ruled paper stock and prevents the loss heretofore had when ruled paper became obsolete.

A further advantage lies in the fact that no pressure adjustment of the ruling device is required upon the paper. When placing paper in the machine it is not necessary to exercise extreme care to assure that the printed lines of ruling are straight with reference to the figures such as is the case when using a prepared ruled paper. This advantage is emphasized when mul-

2

iple copies are being made since it is not necessary to exactly align the sheets of paper.

Other features and advantages of the device of the present invention will be apparent from the following description taken in connection with the accompanying drawing, in which:

Figure 1 is an exploded perspective view of the line printing plates of the present invention and the means for mounting the same in a writing machine;

Figure 2 is an elevational view of the line printing plate of the present invention;

Figure 3 is a diagrammatic view of a writing machine showing the printing plates of the present invention mounted thereon; and

Figure 4 is a fragmentary perspective view partly in section of the writing machine showing the line printing plates in operative position thereon.

20 Although the device of the present invention can be used with or made a part of a number of different writing machines, for the purpose of illustrating the invention it has been shown as a part of a writing machine schematically

25 shown in Figure 3. In the writing machine there shown, the reference character 10 indicates one of a plurality of type-carrying bars mounted for vertical reciprocating movement in a bearing 11. Each bar 10 carries a plurality of type segments 12, the latter being slidably mounted for movement transversely of the bar 10. Although the type segments may be mounted in any manner desired so as to bring about the relative sliding movement, in the illustrated form of the invention each segment is formed with a collar 13 intermediate the ends thereof having a sliding fit in an enlarged bore 14 of the opening of the bar 10 in which the segments are mounted.

The bars 10 are raised to positions necessary to bring selected type segments into printing position by selective operation of one of a plurality of levers 15. To simplify illustration of the invention, only one of the levers 15 has been shown and this lever is pivoted at 16 to the frame of the writing machine. The inner end of the lever 15 is formed with a boss 17 or the like engageable in a notch or re-entrant opening 18 formed at the lower end of each bar 10. Each bar 10 is normally held in a depressed position by a spring 19 which, as will be seen, insures that the notch 18 is held in engagement with the boss 17 of the lever 15. The opposite end of each lever 15 is formed with a key or actuating knob 21 to the end that when key 21 is depressed the opposite end of the lever will

50

55

rise to urge the type bar upwardly to bring the type segment 12 controlled by the particular key and lever combination into printing position relative to a platen 22 over which is to be passed one or more sheets of paper 23.

The bar 10 is held in this elevated position by the engagement between a dog 24 pivotally mounted on the frame of the machine adjacent the lower end of the bar and one of a plurality of ratchet detents 25 formed on the lower end of the bar. The dog 24 is normally urged into engagement with the face of the bar 10 on which the ratchet detents are formed through a link 26 pivotally connected at its one end to the dog and at its opposite end to a lever 27 which in turn is pivotally mounted at 28 to the frame of the machine. A spring 29 having one end fixed to the frame at 30 has the opposite end thereof connected to a lug 31 carried by the link 26. It will be seen that the spring 29 will normally urge the link 26 and the dog 24 to the right as viewed in Figure 3 and thus hold the dog against the face of the bar 10 on which are formed the ratchet detents 25.

The platen 22 is mounted for translational movement through a pair of levers 34, each of which is pivotally connected at its lower end at 35 to the frame of the machine. The upper ends of the lever 34 are rotatably connected respectively to opposite ends of an axle 36 of the core of the platen which coincides with the axis of rotation of the same. Each lever 34 is provided with a laterally projecting arm 37 to which is pivotally connected the armature 38 of a solenoid 39. When the solenoids 39 are energized the armatures 38 thereof move to the left to urge the platen 22 to the left around the pivot points 35 and thus urge the sheet of paper 23 carried by the platen 22 into printing engagement with the ribbon 41.

The solenoids 39 are energized through a circuit which includes a suitable source of current 42 and a normally open switch 43 having an actuating key 44. The switch 43 also controls the circuits of a pair of solenoids 45 mounted on opposite sides of the machine for pivotal movement about an axis 46. Energization of the coils of the solenoids 45 urges the cores 47 thereof outwardly to swing a pair of striker levers 48, each pivoted at 49 to the frame of the writing machine, in a clockwise direction to urge a striking bar 50 extending transversely of the machine and supported by the levers 48 into engagement with hammer pins 51. A hammer pin 51 is carried by the writing machine adjacent the writing position of each bar 10 and is normally held in an inoperative position by a spring 52 acting against a collar 53 having a sliding fit in a carrier member 54 extending transversely of the machine at the writing position.

It will now be seen that depression of the key 44 closes the switch 43 to simultaneously energize solenoids 39 and 45. Energization of the solenoids brings about movement of the platen 22 to the left as viewed in Figure 3 as the striker bar 50 is moved into engagement with the hammer pins 51 which strike the type segments 12 in the writing position to move the segments to the right and into engagement with the ribbon 41 disposed adjacent the paper carried by the platen.

When the key 44 is released the solenoid circuits will be de-energized as the switch 43 will now be opened. The cores of the solenoids are now returned to their normal positions through the action of the springs 55 and 56 connected re-

spectively to the lever 34 and the striking lever 48. The striking lever 48, as it approaches its normal position engages the one end of a coil buffer spring 58 the opposite end of which is adjustably carried by the frame of the machine. It will be seen, referring now to Figure 3, that the momentum of the lever will compress the spring 58 and allow the end 59 of the core 47 of the one solenoid 45 to engage an arm 61 laterally projecting from the lever 27 to rock the lever 26 to the left and thus temporarily disengage the dog 24 from the ratchet detent 25. The bar 10 is now returned to its normal position through the spring 19 which also causes the key 21 to move back into its normal elevated position. The spring 56 will have now moved the striking lever 48 to its normal position in which the end 59 of the core 47 is out of engagement with the arm 61 of the lever 27. With the end 59 out of engagement with the arm 61 the spring 29 will again urge the linkage mechanism comprising the levers 27 and 26 to the right as viewed in Figure 3 to again cause the dog 24 to engage the face of the bar 10 on which the ratchet detents 25 are formed.

In the writing machine just described where it is desired to separate the matter printed into columns it has been the practice heretofore to use a paper having printed lines thereon to divide the printed matter into the columns desired. As a user of such a machine might need to print or record a variety of information calling for differently ruled paper, a large variety and stock of ruled paper must be kept on hand. The device of the present invention obviates this requirement for the device will print at each writing operation a desired number of short parallel lines, which lines will form a corresponding number of continuous column delineating lines co-extensive with the length of the columns of printed matter. Each line-printing device, as best shown in Figure 2, comprises a plate-like member 62 having one end face 63 formed with a radius of curvature corresponding to the radius of curvature of the platen 22 of the machine. Each plate 62 is cut away to form a substantially rectangular opening in the one edge face thereof to provide a web 64 to be completely received in one of a plurality of slots 65 milled or otherwise formed in a bar 66 which is fixed to the carrier member 54 by some fastening means such as the screws 67. The slots 65 are so spaced along the bar 66 that they are disposed between the type-carrying bars 10 to the end that the line printing plates 62 lie between the type segments carried by the bars 10.

To prevent disengagement of a plate 62 from the slot 65 in which it is mounted, a retaining member in the form of a strip 68 is clamped against the top surface of the bar 66 by thumb nuts 69 engaging threaded studs 70 projecting upwardly from opposite ends of the bar 66. This strip carries index means either in the form of numerals engraved in the strip itself or printed or otherwise formed on a band such as shown at 71 and which is permanently carried by the strip 68. The indicia carried by the band indicates to a user the relative positions of the slots 65 and the type segments 12 to facilitate the placing of the line-printing plates 62 into the desired slots 65.

The plates are so mounted in the slots that the curved end faces 63 project toward the platen 22. As the bar 66 is mounted to the carrier member 54 contiguous to the writing position the faces 63 of the plates 62 are disposed intermediate the platen and the normal position of the type face of the segments 12. It will thus be seen

that as the platen is moved toward the segments the paper carried by the platen is brought into printing engagement with the ribbon 41 and the curved end faces 63 of the plates 62. As the curvature of the end faces is substantially that of the platen, the end faces form or print a short line extending in the direction of movement of the paper through the machine.

As these lines will be formed at each printing operation and as each line printed is as long as, or slightly longer than, the spacing of the transverse lines of indicia printed by the segments, continuous lines will ultimately be formed co-extensive with the length of the column or columns of printed indicia. These composite lines, as should now be understood, form column-delineating lines along the paper passed through the machine. Since all of the characters which are to appear on a single transverse line are printed in a single operation, the plates 62 will strike in one place only once, and there will thus be no tendency to cut the paper by repeated blows in the same spot.

The spaces between these columns of delineating lines can be changed at will for it is only necessary to remove the nuts 69 to separate the strip 68 from the bar 66, remove the plates 62 from the slots and then reinsert them into the proper slots. The indicia carried by the band 71 serve, as previously explained, to indicate the relative positions of the slots 65 and the type segments 12 to facilitate the proper positioning of the plates 62.

Although the end faces 63 of the plate 62 are formed to print a continuous line, it is obvious that these end faces may be formed to print any type of delineating mark desired. The end faces, for example, could be formed with a series of protuberances which would form a discontinuous delineating line which might be desirable in some fields of use.

Although the now preferred embodiment of the invention has been shown and described herein, it is to be understood that the invention is not to be limited thereto for the invention is susceptible to changes in form and detail within the scope of the appended claims.

I claim:

1. In a writing machine having a platen upon which at least one sheet of paper is adapted to be mounted, a plurality of horizontally aligned, vertically movable carrier members, a plurality of printing members carried by each carrier member, means for selectively moving one or more carrier members to positions in which preselected printing members carried thereby are moved into operative positions relative to said platen, and means for effecting relative movement between the printing members and said platen to form indicia upon said sheet of paper; a ruling device comprising: a support mounted adjacent said platen; a plurality of printing means having platen-engaging faces formed with line-printing means; means on said support serially formed intermediate said type-carrying members for selectively mounting said line-printing means; index means carried by said support for indicating the position of said printing means relative to said carrier members; and means for holding said line-printing means against movement; whereby operation of said means for effecting relative movement of the printing members and said platen causes a portion of said sheet of paper to be brought into printing relationship between said platen and the line printing means to form

column-delineating lines equal in number to the number of line-printing means mounted to said support.

2. A column marker attachment for a writing machine having a platen upon which at least one sheet of paper is adapted to be mounted and including a plurality of numeral printing members and means for effecting relative movement between said platen and said printing members to form columns of numerals upon said paper, comprising: an elongate supporting bar provided with means for mounting same on said machine adjacent said platen and parallel thereto; a series of spaced slots formed in said bar normal to its longitudinal axis; a plurality of vertical line printing means disposed intermediate said printing members; each of said printing means having a narrow end face conformable to the working surface of said platen and each having a thickness less than the width of said slots so that they may be mounted in selected slots to dispose said narrow platen conforming end face contiguous to said platen; whereby operation of said means for effecting relative movement of said platen and said numeral printing members causes said printing members to print on said paper and simultaneously causes the end faces of said vertical line printing means to form on said paper longitudinally extending predeterminedly spaced column delineating lines intermediate preselected indicia formed by said printing members.

3. A column marker attachment for a writing machine having a platen upon which at least one sheet of paper is adapted to be mounted and including a plurality of numeral printing members and means for effecting relative movement between said platen and said printing members to form columns of numerals upon said paper, comprising: an elongate supporting bar provided with means for mounting same on said machine adjacent said platen and parallel thereto; a series of spaced slots formed in said bar normal to its longitudinal axis; a plurality of vertical line printing means disposed intermediate said printing members; each of said printing means having a narrow end face conformable to the working surface of said platen and each having a thickness less than the width of said slots so that they may be mounted in selected slots to dispose said narrow platen conforming end face contiguous to said platen; and means for removably holding said line printing means in said slots; whereby operation of said means for effecting relative movement of said platen and said numeral printing members causes said printing members to print on said paper and simultaneously causes the end faces of said vertical line printing means to form on said paper longitudinally extending predeterminedly spaced column delineating lines intermediate preselected indicia formed by said printing members.

4. A column marker attachment for a writing machine having a platen upon which at least one sheet of paper is adapted to be mounted and including a plurality of numeral printing members and means for effecting relative movement between said platen and said printing members to form columns of numerals upon said paper, comprising: an elongate supporting bar provided with means for mounting same on said machine adjacent said platen and parallel thereto; a series of spaced slots formed in said bar normal to its longitudinal axis; a plurality of vertical line printing means disposed intermediate said printing members; each of said printing means hav-

ing a narrow end face conformable to the working surface of said platen and each having a thickness less than the width of said slots so that they may be mounted in selected slots to dispose said narrow platen conforming end face contiguous to said platen; an elongated strip of substantially rigid material adapted to overlie said slots and said vertical line printing means; and means for securing said strip to said bar; whereby operation of said means for effecting relative movement of said platen and said numeral printing members causes said printing members to print on said paper and simultaneously causes the end faces of said vertical line printing means to form on said paper longitudinally extending predeterminedly spaced column delineating lines intermediate preselected indicia formed by said printing members.

5. A column marker attachment for a writing machine having a platen upon which at least one sheet of paper is adapted to be mounted and including a plurality of numeral printing members and means for effecting relative movement between said platen and said printing members to form columns of numerals upon said paper, comprising: an elongate supporting bar provided with means for mounting same on said machine adjacent said platen and parallel thereto; a series of spaced slots formed in said bar normal to its longitudinal axis; a plurality of vertical line printing means disposed intermediate said printing members; each of said printing means having a narrow end face conformable to the working surface of said platen and each having a thickness less than the width of said slots so that they may be mounted in selected slots to

dispose said narrow platen conforming end face contiguous to said platen; means for removably holding said line printing means in said slots; and index means carried by said support for indicating the positions of said line printing means relative to said numeral printing means; whereby operation of said means for effecting relative movement of said platen and said numeral printing members causes said printing members to print on said paper and simultaneously causes the end faces of said vertical line printing means to form on said paper longitudinally extending predeterminedly spaced column delineating lines intermediate preselected indicia formed by said printing members.
